FRUIT DICING MACHINE

Brüno Weirauch, Brunswick, Germany, assignor
to Heribert Kricheldorf & Brüser, Maschinen-
fabrik, Brunswick, Germany

Application July 29, 1935, Serial No. 33,792
In Germany June 4, 1934

9 Claims. (Cl. 146—78)

This invention relates to a machine for cutting to pieces carrots, beets and turnips and other bulbous fruits, this improved machine rendering it possible to cut the fruits concerned into strips or cubes without levigating or comminuting them so that losses are obviated. The machine is, besides, extraordinarily efficient, in that it operates at the same time on the entire circumference of a rotary cutting device.

10 My invention is illustrated diagrammatically and by way of example in the accompanying drawings in which Figure 1 is a front-view of a constructional form of the improved machine, Figure 2 is a section in the plane 2—2 of Fig. 1, 15 and Figure 3 is a section in the plane 3—3 of Fig. 2. Figures 4 and 5 show details drawn to a larger scale. Figure 6 is a view similar to Fig. 2 and shows a modified constructional form, Figure 7 is a section in the plane 7—7 of Fig. 6, Figure 8 a perspective representation of a detail forming part of said other constructional form, and Figure 9 is a modification of the driving gearing shown in the righthand half of Fig. 6.

In the drawings, 11 denotes a foundation plate 12 a standard, and 13 an angular ring, these members constituting the frame of the machine. Within said ring is a tubular sheet-metal member 2 which extends downwardly and serves as delivery member for the material cut into pieces. On the top of said ring 13 is fastened a hood-like covering disk 4 by means of screws 3 and in the centre portion of said disk is an aperture 5 through which passes a shaft 6; laterally therefrom a slot 7 is provided in said disk. On the said disk is fastened by means of screws 9 a casting 8 constituting a bearing or, more precisely, two bearings 10 and 11 for a horizontal shaft 12, two bearings 13 for said shaft 6, and two more bearings 14 for a counter-shaft 15. Above the slot 7 is fastened by means of screws 17 a drum-shaped casing 16 which has an aperture located just above the slot 7 and being correspondingly shaped. The casing 16 encloses a centrifugal wheel 18 provided with four centrifugal blades 19. Said wheel 18 is affixed to the hub 20 of a sleeve 21 firmly keyed to the shaft 12. This shaft which is rotatably supported in the bearings 10 and 11 is provided at its other end with a loose pulley and a fast pulley 22 and 23. On the other side of the casing 2 is a feed hopper 24 through which the material to be cut into pieces is introduced into the machine.

On the one side of the slot 7 is a knife 25 affixed to the hood-shaped covering disk 4 by

means of screws 26 which can be adjusted in longitudinal slots 27 of said disk 4. The centrifugal wheel 18 is so arranged in the interior 44 of the casing 16 that it is closely adjacent to the knife 25, there being left only a very narrow gap, but from that place the casing 16 enlarges essentially in the form of a spiral of low pitch along the circumference of the entire casing to the other end of the slot 7.

If carrots, beets or turnips or the like are introduced into the casing 16 through the hopper 24 and if the centrifugal wheel 18 is set in motion, the respective material is cut into disks by means of the knives, the disks leaving then the casing in downward direction. If strips are to be cut a specially designed cutting device (which will presently be described) is secured to the shaft 6 which is rotated from the shaft 12 by the intermediary of the bevel-wheels 28 and 29, the countershaft 15 and the spur-wheels 30 and 31. Said cutting device consists of a disk 32 firmly affixed to the shaft 6 by means of a nut 33. Between the covering disk 4 and the just-mentioned disk 32 so much space is left that a spirally-shaped stationary abutment disk 34 can be arranged in the said disk 4.

At the circumference of the disk 32 is an angular ring 35 affixed by screws; this ring bears in radial slots 36 a large number of wedge-shaped knives 37. The upper ends of these knives extend into a ring 38 which forms, together with the ring 35, the rotary set of cutting knives, or the rotary cutting device respectively. The shape of the wedge-shaped knives 37 is such that the channels 39 left between them neither become narrower nor larger in exterior direction.

The disks into which the carrots or other bulbous fruits have been cut and which leave the covering disk 7 through the slot 7 get into the cutting space which is bounded at its top by said disk 4, at its bottom by the rotating disk 32, at its interior circumference by the abutment disk 34 and at its outer circumference by the rotating set of knives of the rotary cutting device. The disks obtained from the turnips etc. are pressed outwardly in radial direction in the space 40 which becomes gradually narrower, as shown in Fig. 4, the abutment disk leading the turnip disks towards and against the knives 37 which cut them into strips.

If the strips are to be further cut into cubes which operation is known as dicing, knives 41, Figs. 3 and 4, which are arranged tangentially and counter to the direction of rotation of the disk are provided at the outer circumference of the set

50
55

of knives 37. Said knives 41 are affixed to straps 41', at right angles with respect to the same, and said straps serve at the same time for fastening the knives 41 to the lower surface of the hood-shaped covering disk by means of screws 43 set in holes in an annulus fast to said disk 4.

The cubes obtained by the further cutting of the strips fall down through the tubular sheet-metal member 2, e. g., into a basket, chest or the like placed upon the foundation plate 1.

In the constructional form illustrated in Figs. 6-8 there is likewise a cutting device transforming the turnips, etc., into disks but in contrast to the first described constructional form the additional device transforming the disks into strips and into cubes is arranged not horizontally, but vertically whereby the driving members are correspondingly otherwise designed.

On the horizontal shaft 12, which is rotatably supported in the bearings 10₁ and 11₁ and bears the loose pulley and the fast pulley 22₁ and 23₁, and is firmly connected with the centrifugal disk 18₁ by the intermediary of a sleeve 21₁ keyed to said shaft, is a cog-wheel 45 which is likewise keyed to the said shaft and meshes with another cog-wheel 46. This wheel is keyed to a shaft 47 arranged parallel with respect to the shaft 12₁ and supported in the bearings 48 and 49. Keyed to the front end of the shaft 47 is a drum 50 bearing a ring 38₁ secured to it by means of screws 51, and having radial slots into which the radially disposed wedge-shaped knives are inserted. The other ends of these knives extend into slots of a ring 38₁ and form, together with the just mentioned other parts, the rotary knife set by which the disks obtained from the turnips, etc., are further cut into strips. These strips may then be again further cut, into cubes, by knives 41₁ arranged radially at the rotary knife set. The knives 41₁ are connected with straps 41₁, with the aid of which, and by means of screws 43₁, they are affixed to a casing shown perspectively in Fig. 8. This casing 52 encloses the drum 50 which bears the set of knives, i. e. the rotary cutting device, and an abutment member 34₁ by means of which the cutting space 40₁ is gradually reduced in length axially of the knife wheel from the place where the disks enter said space. Owing thereto, the cutting space 40₁ is largest at the delivery end of the preliminary cutting device and is reduced in length in the direction of rotation of the drum 53, the reduction taking place gradually. In proximity to the place where the disks enter, said space is reduced so much that only a narrow gap remains at the rotary set of knives.

There are on the casing two lateral straps 52₁ and 52₂ with the aid of which the casing 52 has secured to it the casing 16₁ by means of screws 15, the casing 52 being integral with the frame 53₁. The set of knives is covered exteriorly with a hood 54 which is provided with a lower delivery opening 55. The material here leaving the hood passes to a shaking conveyor 56 attached to swinging arms 57 and 58 hinged to angle irons 59 provided at both sides of the frame. Said conveyor is actuated by a connecting rod 60 engaging a yoke 61 connected with the said conveyor. Said crank rod is furthermore hinged to a connecting arm 62 affixed to a shaft 63. This shaft is provided with a bevel-wheel 64 which meshes with another bevel-wheel 65 keyed to a shaft 66 supported in the bearing 67 and carrying a sprocket 68 connected with another sprocket 70 by means of a chain 69. The wheel 70 is firmly connected with

the hub of the cog-wheel 46 and is, therefore, moved together with the same.

Instead of making use of a pulley, such as 23₁, for driving the machine illustrated in Figs. 6-8 an electromotor 71 may be employed which is located upon a base plate 72 of the frame 53₁ and drives a wedge-pulley 74 by means of a wedge-belt 73. In this constructional form the rotary motion of the shaft 47₁ is transmitted to the preliminary cutting device by the intermediary of the cog-wheels such as those shown at 45 and 46 (Fig. 6) which turn the shaft 12₁.

I wish it to be understood that I do not limit myself to the constructional forms shown and described merely by way of example. There are, in the arrangements and combinations of parts, various departures possible which do not also constitute departures from the invention. It is, for instance, possible to render the abutment member mentioned and, may be, also the knife practically contacting with the rotary set of knives and subdividing the strips into cubes, rotary and to render said set of knives stationary whereby the same effect will be obtained. My invention and the claims are to cover also this modification. 25

I claim:

1. In a machine for cutting up bulbous vegetables and the like, means for cutting an article into relatively thin slabs in a series of successive operations, and means positioned to receive each such slab and cut it into narrow strips transversely of the slab, said means comprising a support, a circular series of knives arranged about said support, a cam of low pitch arranged to move said slabs slowly through said series of knives, and means arranged to cut said strips crosswise as they emerge from said series of knives.

2. In a machine for cutting up bulbous vegetables and the like, a horizontal knife, means for moving articles past said knife to cut slabs 40 therefrom, a disk below said knife, said disk rotating on a vertical axis and being positioned to receive the slabs as they fall from said knife, means on said disk for cutting the slabs crosswise into strips, means for moving the slabs radially of the disk during such cutting operation, and fixed cutters located tangentially of the disk for cutting the strips into lengths.

3. In a machine for cutting up bulbous vegetables and the like, a circular table, radial knives 50 on said table, means for supplying articles to the table within the series of knives, means for forcing the articles radially outward over said knives for cutting them into strips, said means comprising a cam of low pitch extending substantially around the circumference of the table, said cam and table being relatively rotatable, and a plurality of cutters arranged about said table for cutting the emerging strips crosswise into short lengths.

4. In a machine of the character described, a circular table, radial knives on said table adjacent its outer margin, means for cutting slabs from root vegetables and the like and feeding them to said table in horizontal position, and an eccentric device positioned to feed said slabs outward over said knives, said table and said eccentric device being mounted for relative rotation.

5. In a machine of the character described, a circular table, radial knives on said table adjacent its outer margin, means for feeding slabs to said table, and an eccentric device positioned to feed said slabs outward over said knives, said table and said eccentric device being mounted for relative rotation, said knives being wedge- 75

shaped and so designed that the channels between them are of uniform cross-sectional area.

6. In a machine for cutting up bulbous vegetables and the like, a rotary table, radial knives on said table, means for supplying articles to said table within the series of knives, means for forcing the articles radially outward over said knives for cutting them into strips, and cutting means arranged tangentially of said table, for cutting said strips into shorter lengths.

10 7. In a machine for cutting up bulbous vegetables and the like, means for slicing such articles into horizontally positioned slabs by a series of operations each removing only one slab from an article, a rotary table positioned to receive the slabs directly from such slicing means, means for moving all the slabs in the same horizontal plane while cutting them into strips, and means for cutting the strips into shorter lengths while still maintaining them in the same horizontal plane.

20 8. In a device of the character described, a

circular series of cutters, an article supporting device, means for rotating the cutters and the supporting device, a stationary curved wall substantially coextensive with the series of cutters, said wall being arranged to bear against such articles and to force them progressively toward said cutters during the rotation of said cutters and supporting device, and means for cutting into short lengths the strips formed by said cutters.

10 9. In a device of the character described, a series of cutters arranged in a ring, a cam wall operatively related to said ring, said wall and said ring of cutters having relative rotation, means for feeding slabs into a space between said wall and said cutters, said wall being so arranged as to bear against an edge of a slab and force it flatwise across said ring of cutters, and a fixed blade mounted at the exit side of the ring to dice the strips formed by said cutters as they emerge 15 from said ring.

20 BRÜNO WEIRAUCH.
